BAR OR THE LIKE

Cecilio I. Lazo de la Vega, P.O. Box 554,
Valdosta, Ga. 31601

Filed July 12, 1972, Ser. No. 271,029

Term of patent 14 years

Int. Cl. D6—04

U.S. Cl. D6—144

FIG.1

FIG.2

FIG. 4

FIG. 3

FIG. 5

FIG. 6

FIG. 7

FIG. 1 is a top plan view of a bar showing my new design in fully closed condition;

FIG. 2 is a front elevational view thereof with a portion of the top in opened condition;

FIG. 3 is a right end elevational view thereof in closed position;

FIG. 4 is a partial view similar to FIG. 3 with a portion of the top in opened condition;

FIG. 5 is a rear elevational view thereof;

FIG. 6 is a top plan view of a second embodiment of a bar showing my new design; and

FIG. 7 is a front elevational view thereof.

I claim:

The ornamental design for a bar or the like, substantially as shown and described.
